VANITY CASE

Nathan Kasdan, New York, and Daniel Pollack,
Brooklyn, N. Y., assignors to Majestic Metal
Specialties, Inc., a corporation of New York

Application December 24, 1935, Serial No. 55,952

13 Claims. (Cl. 132—83)

This invention relates to vanity cases and has for its object to provide a plural compartment type which is adapted to fit the hand of the user. Another object is to provide a vanity case having a mirror which is large and also slidable to cover or expose one or two vanity case compartments.

Referring to the drawing, Fig. 1 is a perspective of the vanity case of this invention in which the powder receptacle is held in position for use.

Fig. 2 is a top plan view of the vanity case with the cover removed.

Fig. 3 is a side view of the device of Fig. 2 with the cover in the end position shown in Fig. 1.

Fig. 4 is a section on the line 4—4 of Fig. 2.

Fig. 5 is a section on the line 5—5 of Fig. 7.

Fig. 6 is a section on the line 6—6 of Fig. 7.

Fig. 7 is a perspective of both end portions of the slidable closure with the central portion broken away.

The device illustrated in the drawing comprises a pair of cosmetic receptacles 10 and 11, that having the larger recess being adapted to receive cake powder, and that having the smaller recess being intended for rouge. Each receptacle is connected to the other by a hinge 12, the leaves of which are formed on the outer casing 14 of each container, and both receptacles are closed by a sliding cover or closure 13. Each receptacle is provided with an inner casing 15 having walls forming a cosmetic receiving recess above a bottom ledge 16 and also a deck portion 17 which spaces the recess from the outer casing walls. Longitudinally of each container and transversely of each hinge, are arranged guides 18 formed by an upstanding and bent-over portion of the side wall of the outer casing. Adjacent the guides 18 the inner casing has a portion thereof raised to constitute a track 19 on which the closure may slide without its scraping or sliding on the deck. In each container there is a longitudinal recess 20 formed below the top of the guides, for receiving lugs 21 on the closure 13. The raised track 19 at the end of each container remote from the hinge 12 is widened at 22 to constitute a stop for each closure lug 21 and also serving to position the inner casing laterally within the outer casing. The opposite end of the inner casing from the portions 22 is transversely positioned within the outer casing by means of the lugs 21 as the cover slides back and forth, and also by means of the friction fit given the down-turned transverse edges of the inner casing adjacent and remote from the hinge 12.

The closure 13 comprises a mirror 23 held in

the frame 24 by means of an outer holding frame 25 which is shaped as shown in Figs. 5 and 6. A lower plate 26 is secured to the holding frame 25 by means of lugs 28 which are expanded into holes in the bottom of the holding frame 25 as shown in Fig. 5. A little spreading or upsetting of the metal within the holes tends to bind or clamp the lower plate against the outer holding frame for the mirror. The outer frame 25 is shaped to provide, with the lower plate 26, longitudinal grooves 32 along each side for reception of the horizontal flange portions of the guides 18. A finger piece 31 formed on the outer holding frame 25 assists in pushing or pulling the closure frame along the guides 18.

The adjacent lower transverse edges of the two containers are adapted to contact at 29 to form a stop to prevent the two receptacles from angular displacement more than the very small amount away from the horizontal position in one direction. In the other direction the two receptacles 10 and 11 are adapted for angular displacement until one forms with the other an obtuse angle as shown in Fig. 1. In this last situation adjacent ends of the guides 18 are so shaped at 30 adjacent the hinge 12 as to constitute stops to prevent moving one case relative to the other more than the indicated amount.

In use the sliding closure 13 normally maintains both receptacles in substantial alignment and the friction of the sliding closure in the guides is sufficient to maintain it in a position closing both receptacles. To open the vanity case, the user pushes the finger piece in a direction to slide the closure to the position shown in Fig. 1. If the rouge in the compartment 11 is being used, this smaller receptacle is held in a horizontal position and the other or larger receptacle 10 in an inclined position. For using the powder receptacle 10 it may be held horizontally with the other portion 11 inclined and the mirror 23 extending upwardly and rearwardly. An advantage of the vanity case compartments having no more than the limited angular displacement of one with respect to the other resides in the ability of the two receptacles when fully opened as shown in Fig. 1 to more conveniently fit the user's hand, than would be the case if they did not have such relative angular movement. The loose powder cake with an applicator or puff is adapted to be kept within the larger recess 10 while the rouge cake and its applicator are held within the smaller recess 11. When the closure extends across both receptacles, the mirror is on the outside and adapted for use as a

mirror without opening either receptacle. This is an advantage not possessed by the usual vanity case which more customarily has a mirror mounted on the inside of a cover, for example 5 where the mirror is not adapted for use without opening the vanity case. The closure 13 being movable along the raised track portions 19, is kept from marking or scratching the deck 17 of the inner casing so that this deck portion 10 may retain its initial high polish.

To assemble the vanity case, the inner casings of each receptacle are placed within their outer casings by a friction or some sort of a yieldable fit as is customary in this art. The lugs 21 at 15 one end of the receptacle 11 are placed within the slots 20 of that receptacle before it is hingedly connected to the other. With the closure in position, the hinge pin or pintle is next inserted through the leaves or knuckles of the hinge 12 20 for holding the two portions of this vanity case hingedly connected.

To remove the cover from the two vanity case sections as shown in Fig. 2, it is necessary to pull out the hinge pin, separate the two sections 25 and slide the mirror or cover out the open end of the slot 20 adjacent the hinge. After this the sections may be again hingedly connected as shown in Fig. 2. In order to attach the bottom plate 26 to the outer frame 25, it will be found 30 desirable to first attach the frame 25 to the plate 26, expanding the metal of the frame to retain the plate 26 in position as shown in Fig. 5. After the plate 26 has been attached then the mirror 23 and the inner frame 24 may be secured in 35 position in the outer frame 25 by bending over the retaining flange of the frame 25.

We claim:

1. A vanity case comprising a pair of cosmetic receptacles hingedly connected, stops limiting the 40 movement of said receptacles to substantial alignment in one direction and to the formation of an obtuse angle between them in the other direction, and a closure for said receptacles adapted to hold them in their substantially aligned position.

2. A vanity case comprising a pair of receptacles hinged together, a sliding mirror adapted to cover said receptacles when arranged laterally of one another and with the back of the mirror 50 toward said receptacles, each receptacle being provided along opposite sides with aligned guides in which said mirror is moved.

3. A vanity case comprising a pair of cosmetic receptacles, a mirror closing both receptacles 55 when substantially aligned, a hinged connection between said receptacles adapted to enable angular displacement of one receptacle with respect to the other whereby the pair of them may fit the hand during use, said mirror being movable to uncover both of said receptacles.

4. A vanity case comprising a pair of cosmetic receptacles, a mirror closing both receptacles when substantially aligned, a hinged connection between said receptacles adapted to enable angular displacement of one receptacle with respect to the other whereby the pair of them may fit the hand during use, said mirror being movable to uncover both of said receptacles, said mirror being arranged with its back adjacent the inside 70 of said receptacles, guides on opposite sides of both receptacles along which the mirror may slide to open and close both receptacles, a stop to limit the opening sliding movement of said mirror and another stop to limit closing movement of said 75 mirror.

5. A vanity case comprising a pair of cosmetic receptacles, a mirror closing both receptacles when substantially aligned, a hinged connection between said receptacles adapted to enable angular displacement of one receptacle with respect to the other whereby the pair of them may fit the hand during use, said mirror being movable to uncover both of said receptacles, said mirror being arranged with its back adjacent the inside of said receptacles, guides on opposite sides of both receptacles along which the mirror may slide to open and close both receptacles, a stop to limit the opening sliding movement of said mirror and another stop to limit closing movement of said 1 mirror, a stop to limit angular movement of said receptacles to a position in which one is in substantial alignment with the other, and another stop to limit angular movement of said receptacles to an obtuse angular arrangement of one with respect to the other to fit the hand of a user when said mirror has been opened to uncover both receptacles.

6. A pair of hingedly connected cosmetic containers each provided with guides along which a single closure for both may slide, the guides limiting the angular movement of said containers in one direction.

7. A pair of hingedly connected cosmetic containers each provided with guides along which a single closure for both may slide, the guides limiting the angular movement of said containers in one direction, and the containers contacting to limit the angular movement of said containers in the opposite direction.

8. A vanity case comprising an outer casing, an inner casing forming a recess for receiving cosmetic, and a deck around said recess, a sliding closure and guides along which said closure may slide, said guides being formed by the outer casing, the deck adjacent said guides being raised to keep the 40 closure off said deck, and the raised portion of the deck being longitudinally slotted for receiving a projection on said closure.

9. A closure for a cosmetic container comprising a mirror, a frame for said mirror, and a back 45 plate secured to said frame, the contiguous longitudinal edge portions of said frame and back plate being shaped to constitute guide means adapted to cooperate with guides along said container, whereby said closure may slide with the 50 mirror continually facing outward.

10. A pair of pivotally connected containers having a slidable closure for both, each container having on its upper and open side a longitudinal slot open adjacent the pivot between said containers, a projection carried by the closure adapted to slide in the slot of each container and to move from one slot into the other across said slot, the pivotal connection being arranged to one side of said slot so as not to impede the travel of 60 said projection.

11. A vanity case comprising an outer casing, an inner casing forming a cosmetic receiving recess and deck, a sliding closure for the vanity case, guides formed on the outer casing along 65 which said closure slides, lugs depending from said closure below the deck of said inner casing which is provided with a longitudinal slot on each side to receive one of the closure lugs, said inner casing being laterally in contact with said outer casing adjacent only one end of said longitudinal slots, the inner casing at its other end being laterally positioned to some extent by the fit of the inner casing between the transverse sides of the outer casing and by said lugs of the closure. 70 75

12. A container for toilet articles, comprising a casing and closure therefor, a mirror secured to one of them, a holding frame for the mirror, a plate secured to said frame, contiguous the opposite side from the mirror, said frame and plate being secured together by a projection and recess connection with the projection being headed over to hold it in said recess.

13. A container for toilet articles, comprising a casing and closure therefor, a mirror secured to one of them, a holding frame for the mirror, a

plate secured to said frame, contiguous the opposite side from the mirror, said frame and plate being secured together by a projection and recess connection with the projection being headed over to hold it in said recess, said frame being spaced 5 from the back of the mirror and the projection being on said plate and adapted to be headed over the recess in the frame before the mirror is mounted in said frame.
